UNITED STATES PATENT OFFICE

2,370,607

TYPEWRITER SUPPORT

William H. Schuh, Aberdeen, Wash., assignor
to Grays Harbor Chair & Mfg. Company,
Hoquiam, Wash., a corporation of Washington

Application July 3, 1942, Serial No. 449,636

2 Claims. (Cl. 311—17)

This invention relates to a typewriter table and it is primarily an object of the invention to provide a device of this kind which is adapted to be employed as an adjunct in connection with a desk or other article of furniture having a drawer opening.

It is also an object of the invention to provide a table of this kind which may be readily applied or removed with respect to a desk or other supporting element and wherein the device is provided with means to assure the same being effectively maintained in applied position to assure a steady support for a typewriter placed thereon.

The invention consists in the details of construction and in the combination and arrangement of the several parts of my improved typewriter table whereby certain important advantages are attained, as will be hereinafter more fully set forth.

In order that my invention may be better understood, I will now proceed to describe the same with reference to the accompanying drawing, wherein:

Figure 1 is a view in perspective of a typewriter table constructed in accordance with an embodiment of my invention.

Figure 2 is a view in perspective of the device as illustrated in Figure 1 but in inverted position, and

Figure 3 is a sectional view taken substantially on line 3—3 of Figure 1, the table being shown in applied position, the coacting desk being fragmentarily illustrated.

As disclosed in the accompanying drawing, the improved table comprises an elongated flat board B, the rear portion 1 of which is reduced at opposite sides to a width to allow said rear portion 1 to be readily inserted within a conventional drawer opening 2 in a desk D or the like.

The front or forward portion 3 of the board B is adapted to be of a width greater than the width of the opening 2 and the side edges a of the portion 3 merge with the side edges b of the rear portion 1 by the inwardly and rearwardly directed and relatively short cam edges c, each of which is herein disclosed as disposed on a slight inbow.

The side margins of the rear portion 1 of the board B are defined by the depending flanges 4 extending from the rear end of the board B to a point closely adjacent to the cam edges c. These flanges 4 are co-extensive in length one with respect to the other and the forward ends of these

flanges 4 are connected by a transversely disposed flange 5.

The forward end portions 6 of the flanges 4 extend slightly beyond the lower or free longitudinal margin of the flange 5 while the major portions of the flanges 4 have their free or lower longitudinal edges substantially coplanar with the lower or free longitudinal edge of the flange 5 except at their extreme rear ends the flanges 10 4 are slightly reduced from below, as at 7, in width. The rear ends of the flanges 4 are connected by the cross flange 8 depending from the rear extremity of the board B.

The flanges 4, 5 and 8 are preferably wooden strips cut into desired design and dimensions and which strips are rigidly secured in any preferred manner to the under surface of the board B which is also preferably of wood.

It is also to be noted that the rear extremities 20 of the extended portions 6 have their outer margins merging with the outer or free margins of the flanges 4 by the rearwardly and upwardly inclined cam edges 9.

The rear flange 8 and the major rear portions 25 of the flanges 4 are of such widths as to permit the rear portion of the board to be readily inserted through the drawer opening 2 of the desk D or kindred support and this insertion is facilitated by the reduced portions 7.

30 As the rear portion 1 of the board is forced inwardly through the drawer opening 2, the cam edges 9 will contact with the outer edge of the lower wall 10 of the drawer opening 2 and tighten the rear portion of the board B within the desk 35 D or the like. As illustrated in Figure 3, this action of the cam edges 9 will force the rear portion 1 of the board B up against the conventional guide strip 12 provided at each end of a drawer opening at a point thereabove.

40 As also illustrated in Figure 3, it will be noted that when the board B has its rear portion inserted through the drawer opening 2, the forward portion 3 of the board will be positioned outwardly of the desk D or the like so that a 45 typewriter may be readily placed thereon and it is believed to be obvious that the weight of the typewriter upon this portion 3 will maintain the typewriter in applied or working position.

The cam edges c are adapted to have contact 50 with the end edges of the drawer opening 2 to tightly wedge the applied support against side or lateral movement within the drawer opening 2 and particularly when the drawer opening 2 is of considerable depth.

From the foregoing description it is thought

to be obvious that a typewriter table constructed in accordance with my invention is particularly well adapted for use by reason of the convenience and facility with which it may be assembled and operated.

What I claim is:

1. A support comprising an elongated board having its rear portion transversely reduced at opposite sides, flanges secured to the rear portion of the board adjacent to and longitudinally of the side margins thereof, said rear reduced portion and flanges being insertible through a drawer opening, the free edges of the flanges at the inner ends of the flanges being formed to provide cams for wedging action against the bottom edge of the drawer opening to bind the flanges and board between the top and bottom edges of such opening the inner end portions of the side margins of the rear reduced portion extending outwardly and forwardly toward the side edges of the front portion of the board to provide cams

for wedging action with the end edges of the drawer opening through which the rear portion of the board is inserted.

2. A support for mounting engagement in a drawer opening of an article of furniture, comprising a relatively long board having a width through a portion of its length from one end for insertion into said opening, a flange secured to one side of the board along each edge of the said portion, a camming means formed upon the free longitudinal edge of each flange at the end of the flange remote from the said one end of the board for effecting the wedging of the said portion of the board and the flanges between the top and bottom edges of the drawer opening, and each longitudinal edge of the board at the inner end of the said portion thereof being continued outwardly forming a cam edge for wedging contact with a side of the drawer opening.

WILLIAM H. SCHUH.
